UNITED STATES PATENT OFFICE.

CHARLES D. JACOBS, OF SOUTH ORANGE, NEW JERSEY.

MEANS FOR WATERMARKING PAPER.

1,139,871.

Specification of Letters Patent.

Patented May 18, 1915.

Application filed August 21, 1913. Serial No. 735,563.

To all whom it may concern:

Be it known that I, CHARLES D. JACOBS, a citizen of the United States, and a resident of South Orange, in the county of Essex and State of New Jersey, have invented certain new and useful Improvements in Means for Watermarking Paper, of which the following is a specification.

My invention relates to making watermarks in paper and to the means and method whereby said water marks are produced in the paper, and more particularly, both as to the instrumentalities and methods employed, to making intagliated water marks on those produced by increasing thickness of the paper in parts or the whole of a design over the thickness of the surrounding sheet, and also to those water marks wherein the feature just described is combined or used 20 in a water mark design wherein other parts are thinner than the paper in the surrounding sheet.

Further objects of my invention are to produce such a water-mark design, while avoiding thinning the paper surrounding the design, which thinning of the surrounding paper both destroys the artistic effect of the design and also weakens or impairs the strength of the paper, both of which are 30 very important considerations; also, the above object is equally or even more desirable where the water-mark design comprises both parts of greater and less translucency than the other parts of the sheet.

Additional objects of the invention are to provide for the rapid and economical production of water marks of the kinds described, and of the instrumentalities and devices for producing same; to provide 40 against the destruction and impairment of the design producing instrumentalities and also against the consequent deterioration in the appearance and artistic value of the water-mark itself; to provide instrumentalities and means adapted to produce such water-marks varying widely in size and character, and which also realizes the objects and advantages set forth herein and those apparent herefrom; to provide novel 50 and useful instrumentalities for realizing and effecting the objects and advantages herein enumerated and referred to.

Other objects and advantages will be set forth hereinafter or will be obvious herefrom.

The invention consists in the novel means, articles, constructions, methods, arrangements and improvements herein shown and described.

The accompanying drawings referred to herein and forming a part hereof, illustrate one embodiment of the invention, and with the description serve to explain the principles thereof.

Of the drawings: Figure 1 is a perspective view of a dandy roll; Fig. 2 is an enlarged cross-section on line A—B of Fig. 1; Fig. 3 is an enlarged plan of the central part of Fig. 1; and Fig. 4 is a similar view showing the use of supports around a relatively small design.

In many connections it is very desirable to have water-marks of great artistic value and frequently of striking and original design, and many artistic, striking and original effects can be secured only by reducing the translucency of the paper instead of increasing its translucency, as practised in the art at the present time. Other unusual and original effects are secured by united and contrasted employment in a single design of lines or parts of greater translucency with lines or parts of less translucency than the remainder of the paper.

In making a design of the kind described, in which certain parts of the water-mark are thicker than the normal thickness of the paper, the corresponding parts of the design as formed in the gauze cover sheet of the dandy roll, or other corresponding cover sheet, are sunken or intagliated. That is, those parts of the design are sunk below the general surface of the cover which passes about and rests upon the surface or periphery of the body of the dandy roll. It will be clear, of course, that the pulp mixture running into or being formed into these sunken or intagliated parts of the gauze cover will form a more dense portion in the paper web or sheet representing the corresponding part of the design. If a portion of the cover be raised or embossed and a portion thereof also be sunken or intagliated, the resultant design formed in the

paper web or sheet will be partly more dense and partly less dense than the normal thickness of the paper. It will be clear also that the greater contrast in light and shade 5 and the vastly greater number of varied effects thereby possible adds greatly to the use and effect of water-marks so made.

If a gauze or other cover having an intagliated or sunken design be used with the 10 usual dandy roll body, the design is pressed out of shape and flattened out, thus losing the intended values and effect. Also, the portions of the cover contiguous to such sunken or intagliated portions are raised 15 and inclined upward, giving an undesired and detrimental shaded effect which is not desired. The flattening action on the design is also different in different parts of the design rendering it not only flat but irregular in its various parts. If supports or 20 patches be placed underneath the parts of the gauze or similar cover around and adjacent to the water-mark design to hold or support such adjacent parts and thus prevent sunken or intagliated parts of the 25 design being pressed downward and obliterated or deformed, such supports or patches will cause the cover to make a thin place in the paper around the design, thus weakening 30 the paper and destroying the true and desired effect of the design as reproduced in the paper, as hereinbefore indicated.

Means are provided by the invention for 35 realizing the objects and advantages indicated and also for avoiding the defects and disadvantages enumerated as well as others. There is also provided by the invention a dandy roll body adapted to coöperate with a large number of different water-mark 40 designs of the kind described and varying greatly in size and in the nature or combination of intagliated and raised or relief lines and parts therein.

Referring to the accompanying drawings, 45 illustrating an embodiment of the invention, one form of dandy roll body is indicated generally by reference numeral 1. The periphery of such roll body consists of a plurality of separated members which form a 50 sufficient support for the gauze or other corresponding cover and at the same time permits the water from the pulp to flow through. As illustrated, the surface of periphery of the dandy roll body comprises a 55 plurality of rods or supports 2 arranged longitudinally of the cylinder and connecting, and being supported by, the cylinder heads 3 and 4. These heads may have suitable pintles, or a corresponding shaft. 60 Around said rods or other supports 2 are carried a series of rings 6, which in such illustrated form constitute the outer surface of the roll body, and are the immediate support for the gauze cover 7.

65 In the periphery of the dandy roll, I form

an indented or depressed area 8, or such plurality of such areas as may be necessary or desirable, such depressions being of such area and number and so relatively located or disposed that many different cover sheets 70 may be made carrying designs of different sizes and variously arranged on the sheet to meet the sizes and other requirements of the finished product, or to permit economy in time and money of running a plurality 75 of jobs on one web to be afterward separated and assorted. The same construction may be secured with the dandy roll having a periphery or cover support consisting of a plurality of helically arranged, intersecting 80 strips, or with other particular form of construction of dandy roll body. Into such depression 8 enters the depressed or intagliated portions 9 of the cover 7. When a design is employed of less size than the 85 depression 8, or only the central portion of the design is sunken or intagliated, the surrounding portions of the cover 7 may be supported on parts 10 of gauze, or other suitable material, attached to the under side of 90 the cover 7 around the sunken or depressed parts 9 of the design and located within the depressions 8 in the periphery of the dandy roll body. Thus a plurality of the same designs may be assembled or made in a cover 95 sheet and varied very much in position and the design may vary greatly in size and will fit within said depressions, or a plurality of different designs can be created or impressed in a cover sheet and rest within said depressions, and use may also be made of supports at proper places beneath the cover sheet within the depressions. It will thus be seen that the objects and advantages herein set forth are realized by the invention, 100 together with other objects and advantages. Changes from the illustrated and described embodiment may also be made within the scope of the appended claims.

What I do claim as my invention and desire to secure as Letters Patent, is:—

1. A dandy roll including in combination a body having a depressed area in its periphery, a cover sheet fitting closely over the periphery of said dandy roll body, said cover sheet having therein a sunken or intagliated design, the depressed area in said dandy roll containing the intagliated design. 115
2. A dandy roll including in combination a body having a depressed area in its periphery, a cover sheet fitting closely over the periphery of said dandy roll body, said cover sheet having therein a sunken or intagliated design, the depressed area in said dandy roll containing the intagliated design, the design being of less extent than said area, and supporting members arranged beneath said cover and about said design within said depression. 120
3. The combination with a dandy roll 125

body having a depressed area in its periphery, of a plurality of interchangeable cover sheets, each of said sheets adapted to fit closely around the dandy roll body, and each sheet carrying a sunken or intagliated design adapted to be contained within said depressed area, said designs varying in area or extent and occupying correspondingly more or less of said depression.

4. The combination with a dandy roll body having a depressed area in its periphery, of a plurality of interchangeable cover sheets, each of said sheets adapted to fit closely around the dandy roll body, and each sheet carrying a sunken or intagliated design adapted to be contained within said depressed area, said designs varying in area or extent and occupying correspondingly more or less of said depression and supports beneath a cover sheet around said sunken design and within said depressed area in the periphery of the dandy roll body when the design is of less area or extent

than said depressed area in the dandy roll body.

5. The combination with a dandy roll body having a plurality of depressed areas formed in its periphery, of a plurality of interchangeable cover sheets, each of said sheets adapted to fit closely around the dandy roll body, said cover sheets each carrying a plurality of intagliated or sunken designs, said designs being of various sizes and variously arranged upon the respective sheets, but all being arranged so as to fit within said depressions in said dandy roll body when the particular cover sheet is mounted upon the dandy roll body.

In testimony whereof, I have signed my name to this specification, in the presence of two subscribing witnesses.

CHARLES D. JACOBS.
